(57) **CLAIM**

The ornamental design for a bottle, as shown and described.

DESCRIPTION

FIG. 1 is a perspective view of a bottle showing my new design, the exterior surface of the bottle body being reflective;

FIG. 2 is a front elevational view thereof, the rear elevational view being identical;

FIG. 3 is a right side elevational view thereof, the left side elevational view being identical;

FIG. 4 is a top plan view thereof; and,

FIG. 5 is a perspective view of a second embodiment of the bottle depicted in FIGS. 1-4, the sole difference being that the bottle transmits light.

The dotted lines outlining the neck and opening of the bottle depicted in the foregoing figures illustrate environmental structure only, and form no part of the claimed design. The bottom of the bottle depicted in FIGS. 1-5 is not illustrated because it forms no part of the claimed design. Moreover, the surface(s) or portion(s) of the bottle not shown in the figures or otherwise described in the specification form(s) no part of the claimed design.
